CLAIM

The ornamental design for a motorcycle grip, as shown and described.

DESCRIPTION

FIG. 1 is a perspective view of a motorcycle grip of the present invention.

FIG. 2 is a first side elevation view of the motorcycle grip of FIG. 1.

FIG. 3 is a second side elevation view of the motorcycle grip of FIG. 1.

FIG. 4 is a third side elevation view of the motorcycle grip of FIG. 1, which is opposite the first side elevation view of FIG. 2.

FIG. 5 is a fourth side elevation view of the motorcycle grip of FIG. 1, which is opposite the second side elevation view of FIG. 3.

FIG. 6 is an end view of the visible end of the motorcycle grip of FIG. 1; and,

FIG. 7 is an end view of the opposite end of the motorcycle grip of FIG. 1.

Those portions of the motorcycle grip shown in broken lines are included for illustrative purposes only and form no part of the claimed design.
